UNITED STATES PATENT OFFICE

120,129

DESIGN FOR A RING MOUNTING

Morris Mann, Brooklyn, N. Y.

Application January 10, 1940, Serial No. 89,380

Term of patent 7 years

To all whom it may concern:

Be it known that I, Morris Mann, a citizen of the United States, residing at 48 Winthrop Street, in the Borough of Brooklyn, county of Kings, and State of New York, have invented a new, original, and ornamental Design for a Ring Mounting, of which the following is a specification, reference being had to the accompanying drawing, forming part thereof.

Fig. 1 is a side view of a ring mounting showing my new design;

Fig. 2 is a top plan view; and

Fig. 3 is an enlarged perspective view of a fragmentary portion thereof.

I claim:

The ornamental design for a ring mounting, as shown.

MORRIS MANN.
